GEAR CASE FOR MAGNETIC SEPARATOR DRIVE

Karl J. Hnatko, Hibbing, Minn., assignor to Taconite
Engineering & Manufacturing Co., Hibbing, Minn.

Filed Apr. 30, 1973, Ser. No. 355,514

Term of patent 14 years

Int. Cl. D15—09

U.S. Cl. D55—1 G

FIG. 1

FIG. 2

FIG. 3

FIG. 4

FIG. 1 is a right side elevation of a gear case for magnetic separator drive showing my new design, the left side elevation being a mirror image thereof;

FIG. 2 is a front elevation thereof;

FIG. 3 is a top plan view thereof; and

FIG. 4 is a rear elevation thereof.

I claim:

The ornamental design for a gear case for magnetic separator drive, as shown and described.
